UNITED STATES PATENT OFFICE.

CHARLES HANSEN, OF DAVENPORT, IOWA, ASSIGNOR TO DAVENPORT MACHINE AND
FOUNDRY COMPANY, OF DAVENPORT, IOWA, A CORPORATION OF IOWA.

DESIGN FOR A HEAD FOR STREET-LAMP STANDARDS.

Application filed August 24, 1925. Serial No. 14,569. Term of patent 14 years.

To all whom it may concern:

Be it known that I, CHARLES HANSEN, a citizen of the United States, residing at Davenport, in the county of Scott and State of Iowa, have invented a new, original, and ornamental Design for a Head for Street-Lamp Standards, of which the following is a specification, reference being made to the drawing, forming a part thereof.

In the annexed drawing, Fig. 1 is a view in elevation and Fig. 2 is a plan view of a head for street lamp standards in accordance with my invention.

I claim:

The ornamental design for a head for street lamp standards as shown.

CHARLES HANSEN.
